UNITED STATES PATENT OFFICE.

WILLIAM P. BETTENDORF, DECEASED, LATE OF BETTENDORF, IOWA, BY JOSEPH W. BETTENDORF, ADMINISTRATOR, OF BETTENDORF, IOWA.

UNDERFRAME FOR DUMPING-CARS.

1,062,689.

Specification of Letters Patent.

Patented May 27, 1913.

Original application filed March 5, 1910, Serial No. 547,569. Divided and this application filed May 29, 1911. Serial No. 630,188.

To all whom it may concern:

Be it known that WILLIAM P. BETTENDORF, deceased, late a citizen of the United States, residing at Bettendorf, in the county 5 of Scott and State of Iowa, did invent certain new and useful Improvements in Underframes for Dumping-Cars, of which the following is a full, clear, and exact description.

- 10 1.0 This invention relates to the underframes of dumping cars, and particularly to that type of dumping cars, whose bodies are adapted to be lifted from their trucks, such as those set forth and claimed in a copending application for patent, filed by said WILLIAM P. BETTENDORF, on March 5, 1910, Serial No. 547,569, of which this application is a division and which resulted in Patent No. 1,039,638, dated Sept. 24, 1912.
- 15 20 2. The objects of this invention are to provide an economically constructed underframe for a dump-car body, so that the tilting of said body can be accomplished without affecting the relation of the body-bolster to the truck-bolster.

It is also an object of this invention to construct an underframe that will lower the floor of a tilting dump-car so as to obtain as low a center of gravity as possible 30 without striking the flange or rim of the wheels, which especially adapts the car for use in mines, subways and similar work.

These and other objects are accomplished by the means and in the manner hereinafter 35 fully described and as more particularly pointed out in the claims, reference being had to the accompanying drawings forming a part hereof, in which,

Figure 1 is a top plan view of the underframe of one-half of a dump car embodying said invention. Fig. 2 is a bottom plan view of the same removed from the trucks. Fig. 3 is a transverse vertical section taken on dotted line 3-3, Fig. 1. Fig. 4 is a 40 view similar to Fig. 3 showing the car in its tilted position. Fig. 5 is an end view of said car illustrating the means for manipulating the jointed braces, and the hooks, for maintaining the car in its tilted position, or 45 50 in its horizontal position. Fig. 6 is a view similar to Fig. 3 showing the car converted to a "rigid" body.

In the drawings A, A, represent Z-bar

side-sills; B, B, center-sills, and C the end-sills. The end-sills are, preferably, made 55 of cast metal, and the central portion of its inner side extends in the horizontal plane of the floor of the car, inward toward the body-bolster, to a point about midway between the transverse plane of the pivot of 60 the truck and the end of the car, and its rear edge portion is provided with a depressed seat α in which the lower flanges of the center-sills are seated and suitably secured so that their upper surfaces are in 65 the same plane as the upper surface of said extension c .

The body-bolster comprises two parts, which may be the bolster proper and the "cradle". The bolster consists, preferably, 70 of a transverse cast metal beam extending from side-sill to side-sill of the car, the central part of which is rectangular in cross section and tubular and the portions between this central part and its ends are 75 channeled and the lower edges of the side-walls of said channeled portions are flanged inward. The top of this bolster "proper" consists of a flat upper plate, D, the upper surface of which is in the same horizontal 80 plane as the upper surface of the upper flanges of the center-sills and side-sills, and the lower portion thereof has its vertical parallel side-walls d separated a distance less than the width of said top-plate, D, and 85 is bellied downward so that the depth thereof is greatest at its center of length and so that the lower side thereof is curved to enable it to rock from one side to the other on its lower edges. The lower 90 side edges of said bolster are provided with recesses E, which are, preferably, oppositely arranged in pairs in the same transverse plane, and so that each pair will be equal distances apart. The center of length 95 of the upper portion of this bolster is provided with a suitable transverse depressed seat f of sufficient dimensions to permit the passage of the center-sills B, B, and which is of such depth that the upper surfaces of 100 the upper flanges of said sills will be in the same horizontal plane as the upper surface of the bolster.

The ends of the bolster are seated upon the inturned lower flanges of the Z-bar side 105 sills A, and are suitably secured thereto by

rivets or otherwise, and the floor G of the car, which consists, preferably, of a single sheet metal plate, extending from end to end and side to side of the car, is riveted to the center-sills, the side-sills and bolsters of the underframe.

The bolster rests upon and is seated in a cradle consisting of a transverse channeled beam H, the bottom plate or web of which 10 extends in a straight horizontal plane from end to end, and is provided at the inner angles of the lower flanged edges of its sidewalls with protuberances that constitute teeth or cogs g that are adapted to be engaged by the recesses E in the lower edges of the bolster. It is preferable to arrange these cogs g and recesses E so that there will be one at the centers of length of the bolster and cradle in the longitudinal plane of the 20 king-bolt of the truck, and an equal number between the same and each end of the bolster. Thus, when the floor of the car is in its normal horizontal position the central cogs and recesses will be in engagement, and 25 when the car is tilted the engagement of said cogs and recesses will prevent the car-body from slipping upon said cradle H and thus injure their proper relation.

At its center of length the cradle has a 30 suitable male center-bearing e made integral with and depending from its under surface that is adapted to engage a suitable female bearing y of any of the usual types of car-trucks.

35 The means for tilting the body of the car preferably comprise a toggle or jointed brace or strut consisting of two members having their adjacent ends pivotally connected together, one member J of which has its upper 40 end pivotally connected to the inside of the side-walls d of the bolster while the other member J' (which is hinged or pivoted to member J) has its lower end pivotally secured to the bottom of the cradle H in a 45 plane slightly beyond the vertical plane of the pivot from member J. A lateral arm k projects from member J through a segmental slot K in the adjacent side wall of the bolster where it is secured to a link I. 50 The opposite end of said link is pivotally connected to a relatively short arm or crank h rigidly mounted on a rock-shaft a whose ends are journaled in suitable bearings in the car end-sills C and which is rocked by 55 means of a hand-lever b on the extended end thereof.

In order to maintain the body in normal 60 position hooks L are provided and depend from the ends of the bolster "proper" so that they will engage or catch under the ends of the cradle as shown in Fig. 3. When, however, it is desired to convert the car to a rigid body type the upper toggle member J and its actuating parts such as link I, crank 65 h, and rock-shaft a, and the hooks L are

removed while the upper end of the lower toggle member J' is secured to the former pivotal lug of the upper member, substantially as shown in Fig. 6 of the drawings.

What is claimed as new is:—

1. In a dump-car an underframe comprising end-sills, having integral rear extensions that are provided with depressed seats in which the center-sills are secured, center-sills, integral body-bolsters having transverse depressions in the upper part of their central portions in alinement with the seats in the rear extensions of said end-sills in which said center sills are secured and supported, and side-sills secured to the ends of said body-bolsters and provided with flanges that project beyond the longitudinal planes of the ends of said bolsters, the upper surfaces or edges of said bolsters and the upper flanges of all of said sills being disposed in the same horizontal plane and each adapted to contact with and support the floor of the car. 70 75 80 85

2. In a dump-car an underframe comprising side-sills, body-bolsters carried by said side-sills and having transverse depressions in the upper part of their central portions, center-sills extending past said bolsters and secured in the depressions therein, end-sills, and an integral rear extension for each end-sill having a depressed seat in longitudinal alinement with each other and with the bolster depression in which the ends of said center-sill are secured, said bolsters and all of said sills including said end-sill rearward extensions having their upper surfaces disposed in the same horizontal plane and each adapted to contact with and support the floor of the car. 90 95 100

3. In a dump-car an underframe comprising side-sills, body-bolsters carried by said side-sills and having transverse depressions in the upper part of their central portions, center-sills extending past said bolsters and secured in the depressions therein, imperforate end-sills, and an integral rear extension for each end-sill having a depressed seat in longitudinal alinement with each other and with the bolster depression in which the ends of said center-sill are secured, said bolsters and all of said sills including said end-sill rearward extensions having their upper surfaces disposed in the same horizontal plane and each adapted to contact with and support the floor of the car. 105 110 115 120

4. In a dump-car an underframe comprising side-sills, center-sills extending continuously and terminating mediate the bolster and the ends of the car, end-sills, central integral rearward extensions for said end-sills to which the ends of said center-sills are secured, and integral body-bolsters carried by said side-sills and having their central portions recessed in longitudinal alinement with the rear extensions of said end- 125 130

sills in which recess said center-sills are supported, all of said sills and said bolsters having their upper surfaces disposed in the same horizontal plane and each adapted to contact with and directly support the floor of the car.

5. In a dump-car an underframe comprising side-sills, end-sills, having rearward extensions provided with depressed seats 10 in which the center-sills are secured, center-sills, said side-sills and center-sills made of integral rolled metal beams, and a body-bolster supporting said center-sills and consisting of two superimposed members the 15 upper member of which is movable and made of integral cast-metal and the lower relatively stationary member to which said upper member is connected is provided with center-bearings, said upper member provided with a depression through which said center-sill passes and is seated.

6. In a dump-car an underframe comprising side-sills, end-sills, having rearward extensions provided with depressed seats in 25 which the center-sills are secured, center-sills, said side-sills and center-sills made of integral rolled metal beams, and a body-bolster supporting said center-sills and consisting of two superimposed members the 30 upper member of which is movable and made of integral cast-metal and the lower relatively stationary member which is of

less length than and to which said upper member is connected is provided with center-bearings, said upper member provided 35 with a depression through which said center-sill passes and is seated.

7. In a dump-car an underframe comprising side-sills, end-sills, having rearward extensions provided with depressed seats in 40 which the center-sills are secured, center-sills, said side-sills and center-sills made of integral rolled metal beams, and a body-bolster consisting of two superimposed members the upper member of which is 45 movable and made of integral cast-metal and the lower relatively stationary member which is of less length than and to which said upper member is connected is provided with center-bearings, said upper bolster 50 member having a transverse depression in the upper part of its central portion in alignment with the seats in the rearward extensions of said end-sills and in which said center-sills are supported. 55

Signed at Bettendorf, Scott county, Iowa, May 25th 1911.
